United States Patent Office.

JAMES P. SMITH, OF CHERRY HILL, PENNSYLVANIA.

Letters Patent No. 77,329, dated April 28, 1868.

IMPROVEMENT IN EXCAVATING-VEHICLES.

The Schedule referred to in these Letters Patent and making part of the same.

TO ALL WHOM IT MAY CONCERN:

Be it known that I, JAMES P. SMITH, of Cherry Hill, in the county of Erie, and State of Pennsylvania, have invented a new and improved Excavating-Vehicle; and I do hereby declare that the following is a full, clear, and exact description thereof, which will enable those skilled in the art to make and use the same, reference being had to the accompanying drawings, forming part of this specification.

This invention relates to a new and improved vehicle or self-loading wagon, which may be used for excavating the earth in the process of grading, or in moving earth from one place to another; and the invention consists in arranging a shoe or hollow band on an excavating-wheel, or a wheel with revolving buckets, the position of which buckets is controlled by a lever through an eccentric, as will be hereinafter described.

Figure 1 represents a side elevation of the vehicle, showing the excavating-wheel, which, in diameter, corresponds, or nearly so, with the rear wheels of an ordinary wagon. In this case the excavating-wheel takes the place of one of these wheels.

Figure 2 gives a view of the eccentric.

Figure 3 is a vertical section through the lines xx and $x'x'$, showing the form of the wagon-body and the excavating-wheel.

Figure 4 is a view of the lever, arranged on the opposite side of the wagon for the purpose of dumping the load.

Similar letters of reference indicate corresponding parts.

A represents the wagon-body.

B is the excavating-wheel.

C is a semicircular hollow band, which partially surrounds the wheel B.

D represents the buckets or elevators, which project from the periphery of the wheel, with shanks which extend inwards towards the centre of the wheel to the eccentric.

F is the eccentric.

This eccentric is movable by means of the rod α and lever H.

The rod α is attached to the short arm J, as seen in the drawing.

On the shanks or inner ends of the buckets there are friction-rolls, as seen in fig. 2, and the eccentric, F, forms a recess or groove, in which the rolls revolve.

The eccentric is placed loosely on the axle, but eccentrically, so that when it is partially revolved, the position of the buckets is changed.

As seen in the drawing, the buckets are in a position to operate, as it will be noticed that the buckets protrude from the periphery of the wheel, the throw of the eccentric being downward.

Now, if the lever H is thrown forward, so that it would rest in the recess c in the stop-plate d, on the edge of the wagon-body, the throw of the eccentric would withdraw the buckets from the forward and lower portion of the periphery of the wheel, and the same motion of the lever H would throw back the hollow band C, by the rod f, which is attached to the lower end of the lever H, and to the band. In this condition the excavating-wheel would only act the part of a wagon-wheel for transporting the load; but returning to the position shown in the drawing, the excavator is operating, or the wagon is being loaded.

On the lower end of the hollow band C, there is a shovel or scraper, K, which, as the wagon moves along, excavates the earth, and the motion forces the earth into the scraper, while the revolving buckets D, which pass through the rim of the wheel, carry the earth upward and around the wheel, and discharge it into the chute L, from whence it slides into the wagon.

The hollow band C is stationary over the wheel, except as it is moved by operating the lever H.

The wagon-body is something in the form of a hopper, with a movable or drop-bottom which is marked m. This bottom is held up by buttons n, which are operated or turned by the lever o and rod P, as seen in fig. 4.

It will be seen that the wagon is self-loading, and that, when loaded, the contents can be transported and

dumped as may be desired, and that it may be used to good advantage in making and repairing roads, and for grading railroads, and all similar purposes.

Having thus described my invention, I claim as new, and desire to secure by Letters Patent—

1. The combination of the shovels D, provided with friction-rolls, with the eccentric, F, and wheel B; said eccentric being adjusted by means of a rod, a, and lever H, all constructed, arranged, and operating as and for the purpose herein shown and described.

2. I claim the hollow band C, provided with a scraper, K, in combination with the wheel B, when said band is adjustable simultaneously with the eccentric, F, by means of the rod f and lever H, all constructed and arranged as described, and for the purpose specified.

The above specification of my invention signed by me, this 13th day of August, 1867.

JAMES P. SMITH.
